Fig. 7

FIG. 1 is a top perspective view of a wristlet for a bowler showing my new design;

FIG. 2 is atop plan view thereof;

FIG. 3 is a bottom plan view thereof;

FIG. 4 is a side elevational view thereof as viewed from the bottom of FIG. 2;

FIG. 5 is a rear elevational view thereof as seen from the right-hand end of FIG. 4;

FIG. 6 is a side elevational view thereof as seen from the right-hand side of FIG. 5; and

FIG. 7 is a front elevational view thereof as seen from the right-hand end of FIG. 6.

This is a continuation of my copending application Ser. No. D. 16,744 now abandoned.

I claim:

The ornamental design for a wristlet for a bowler, substantially as shown and described.
